UNITED STATES PATENT OFFICE.

GUSTAV L. KIMMERLE, OF NEWARK, AND DIRK S. LANDSTRA, OF SOUTH ORANGE,
NEW JERSEY.

PORTABLE FOLDING OUTSIDE WINDOW-SEAT.

1,365,695.

Specification of Letters Patent. Patented Jan. 18, 1921.

Application filed April 15, 1919. Serial No. 290,350.

To all whom it may concern:

Be it known that we, GUSTAV L. KIMMERLE and DIRK S. LANDSTRA, citizens of the United States, and residents of Newark, county of Essex, and State of New Jersey, and South Orange, county of Essex, and State of New Jersey, have invented certain new and useful Improvements in Portable Folding Outside Window-Seats, of which 10 the following is a specification.

Our invention relates to a seat or support adapted to be removably attached to a window sill and to extend outside the window for use in washing windows, painting, setting glass and the like. When not wanted, it may be readily detached and folded up, and put away in small space until it is again needed.

The invention consists in the improvement 20 of devices of the character referred to in a number of respects, as will be pointed out and claimed.

In the drawings forming a part of this specification, Figure 1 is a side view of a 25 seat embodying my invention in place in a window. Fig. 2 is an end view with parts broken away. Fig. 3 is a top plan view of the seat when folded up ready to be put away, and Fig. 4 is a perspective view of 30 the seat viewed from beneath.

The floor on which the user sits or stands is designated by the reference numeral 10 and may be conveniently made of wood. It has angle irons 11 and 12 across the under- 35 side thereof at front and back respectively, the term "front" being used herein to designate the part next to the window.

Rods 13, 14 pass through alined openings in these angle irons. These rods are formed 40 into hooks 15 at their front ends to be hooked over the stool of the window sill 16 and are provided with suitable cushioning material to prevent injury to the woodwork, as, for example, pieces of rubber tubing 17 may be 45 pulled over the hooked portions 15 to protect the window sill. The outer ends of the rods are threaded and nuts 18 are screwed thereon and serve both as holding and adjusting means for the rods. By screwing 50 up or unscrewing the nuts, the device may be accommodated to varying window, etc., dimensions, as will be readily understood.

The rods 13, 14 also pass through eyes 19 formed in a flat bar 20, secured to the under- 55 side of floor 10 intermediate the angle irons

11 and 12. The eyes 19 in bar 20 are alined with the openings in the angle irons.

The braces 21, 22 for supporting the seat are mounted on the rods 13, 14 so as to be movable endwise thereon and also to turn 60 thereon in folding up or collapsing the device. These braces are preferably of metal and of skeleton form substantially as shown. They are provided with sleeves 23 and 24. The rods 13, 14 pass through these sleeves. 65 Clamping means are provided for clamping the braces on the rods. In the form shown the outer sleeve 24 has a thumb screw 25 threaded therein for this purpose. Extensions of the brackets are provided as shown 70 at 26 for limiting the outward swing of the brackets and to assist in holding the floor 10 in proper relation and preventing sidewise movement thereof. The bar 20 with its eyes 19, is preferably located between the sleeves 75 23, 24, as shown.

The lower ends of the brackets 21, 22 preferably extend forwardly as shown at 27, 28, and are detachably connected by a foldable buffer strip 29, which is preferably made of 80 wood, and is hinged to one bracket and detachably clamped to the other. In the form shown the leg 27 of the bracket 21 is received between the buffer 29 and a piece of metal 30 secured thereon so the buffer strip 29 is 85 rotatable with respect to bracket 21 and a spring clamping member composed of spring parts 31, 32 serves to detachably embrace the leg 28 of bracket 22.

Braces 33, 34 are preferably provided for 90 holding the brackets 21, 22 rigid, serving substantially the purpose of corner braces. Both braces are preferably made from a single bar or piece of heavy wire. They are hinged to the under side of the floor 10 by 95 having the connecting portion 35 thereof passed between the floor and pieces of metal 36, 37 in a manner similar to the hinged connection between buffer strip 29 and bracket leg 27. At their outer ends braces 33, 34 100 have U-shaped or slotted portions 38, 39 adapted to clasp the brackets 21, 22 from beneath. Being of spring material they may be readily sprung into place and sprung out of place when the device is to be folded up. 105

The floor 10 may be left bare on its upper face as in Fig. 4, but preferably it has a collapsible guard or rail on the sides and rear, as shown in the other figures of the drawings. The same may comprise side frames 110

40, 41, hinged in studs 42 secured to the floor 10 along the sides thereof and a rear rail 43, here shown as a board, hinged to the floor at 44, 45. The board 43 has slotted catches 46, 5 47 at its upper corners to detachably engage the side frames 40, 41.

The operation and use of a device in accordance with the invention can now be readily understood. When purchased by a 10 householder, for example, the nuts 18, 18 are adjusted to suit the window sills, thickness of wall, etc. It is attached by hooking the hooks 15 over the window stool. It will be observed that the rods 13, 14 have a 15 slight upward bend back of the hooks 15, 15 so that the engagement is at the edge only and the upper surface of the stool is not touched by the rods and therefore no injury to the woodwork can result from placing the 20 seat in a window. The buffer strip 29 rests against the outside of the house and when made of wood, as is preferable, prevents any metal parts from coming directly against the wall to injure the paint or the like. The 25 rails or guards serve to protect the user when seated or standing on the floor 10.

To remove the device from the window it is merely raised up and unhooked and is then ready for use in another window, or 30 to be collapsed and put away. To collapse the under brackets, the corner braces 33, 34 are sprung out and may then be folded as indicated in dotted lines in Fig. 3.

Upon disengaging the buffer strip 29 from 35 the leg 28 of bracket 22 the brackets 21, 22, may be folded inwardly, and the buffer 20 rearwardly, as indicated in Fig. 3 and the rods 13, 14 may be turned over to the position of Fig. 3, if desired.

40 To fold the seat guard or rail the side brackets 40, 41 are disengaged from catches 46, 47 by turning the board 43 inwardly on its hinges. Then board 43 is folded down until it rests on the floor boards, and 45 then the side brackets 40, 41 are folded in and rest on top of the board 43 as shown on Fig. 3.

It will be seen that a seat in accordance with our invention can be readily and 50 cheaply constructed of wood and metal, and can be made very strong and safe and at the same time be light and portable. It can be adjusted to meet a variety of conditions, both by adjusting the position of the 55 floor with respect to the hooks, and by adjusting the supporting brackets in and out on their rods, which adjustments may be separately performed. When not wanted for use it may be readily folded flat so as

60 to require very little storage space and when it is to be used it can be as readily expanded

and securely clamped with the parts in extended relation.

The form shown is for illustration and for affording a clear understanding of our invention only. Changes and modifications within the scope of our claims may be resorted to without departing from the spirit of the invention or sacrificing the advantages thereof. 70

We claim:

1. In a device of the class described, the combination of a floor member, hooks for attachment to a window sill, brackets pivotally supported beneath the floor member, 75 and a cross connecting member having a hinged connection to one of said brackets and having a detachable connection with the other one of said brackets.

2. In a device of the class described, a 80 floor member, rods extending thereunder and having hooks to engage a window sill, means for adjusting the floor member in and out on said rods, brackets mounted to turn and to slide on said rods, and a connecting member hinged to one of said brackets and detachably clamped to the other of said brackets. 85

3. In a device of the class described, a floor board, angle irons thereunder, rods 90 extending through openings in the angle irons, hooks on said rods for engaging a window sill, a pair of brackets sleeved on said rods between the angle irons, and a buffer strip connecting said brackets. 95

4. In a device of the class described, a floor board, angle irons secured to the under side thereof, rods passing through openings in the angle irons and having hooks adapted to engage a window sill, the 100 rods being threaded at the ends opposite the hooks and having nuts screwed thereon whereby the floor board may be adjusted in and out relative to said hooks, brackets sleeved on said rods and having means 105 to clamp same in adjusted position thereon, a buffer strip detachably connecting said brackets, and corner braces hinged to said floor board and adapted to detachably engage and hold said brackets. 110

5. In a device of the class described, a floor board, a foldable guide rail on its upper side, foldable supporting means on its lower side, and hook members for engaging a window sill and adapted to be 115 turned with the flat sides of the hooks substantially parallel to the floor board.

In testimony that we claim the foregoing, we have hereto set our hands, this 14th day of April, 1919.

GUSTAV L. KIMMERLE.
DIRK S. LANDSTRA.
